OTHER PUBLICATIONS

Exemplary picture of a chair that was on-sale and in public use before the filing of U.S. Appl. No. 29/740,777, filed Jul. 7, 2020. The chair shown in the exemplary picture is offered for sale and sold by Torrans Manufacturing Co. of Jefferson Texas, under the name Bellaire Metal Lawn Chair, and is representative of chair designs on sale and in public use prior to Jul. 7, 2020.

Primary Examiner — Kevin K Rudzinski

Assistant Examiner — Clare Ann Gannon

(74) *Attorney, Agent, or Firm* — Gardner, Linn, Burkhart & Ondersma LLP

(57) **CLAIM**

The ornamental design for a removable chair pad, as shown and described.

DESCRIPTION

FIG. 1 is a top-right perspective view of a removable chair pad showing my new design, in a use condition;
FIG. 2 is a front elevation thereof;
FIG. 3 is a left side elevation thereof;
FIG. 4 is a right side elevation thereof;
FIG. 5 is a back elevation thereof;
FIG. 6 is a top plan view thereof;
FIG. 7 is a top plan view thereof, in a removed condition;
FIG. 8 is a bottom plan view thereof, in a removed condition;
FIG. 9 is a left side elevation thereof, in a removed condition, the right side comprising of a mirror image thereof; and,
FIG. 10 is an end elevation thereof, in a removed condition. The broken lines in the drawings depict environmental structure that form no part of the claimed design.

1 Claim, 9 Drawing Sheets
